UNITED STATES PATENT OFFICE.

CHARLES L. PAINE, OF MILWAUKEE, WISCONSIN.

MUSHROOM LIGHT.

Application filed July 12, 1924. Serial No. 725,664.

To all whom it may concern:

Be it known that I, CHARLES L. PAINE, a citizen of the United States, and resident of Milwaukee, in the county of Milwaukee and State of Wisconsin, have invented certain new and useful Improvements in Mushroom Lights; and I do hereby declare that the following is a full, clear, and exact description thereof.

10 My invention refers to traffic indicators, and it has for its object to provide a traffic indicator of the mushroom type having means for illuminating the same from a remote fixed source entirely independent of 15 the mushroom.

Another object of my invention is to utilize, under certain conditions, standard overhead street lamps for the purpose of illuminating the mushroom, whereby such lamps, 20 in addition to performing their usual functions at street crossings, will also serve to illuminate the traffic signal thereunder.

Heretofore, traffic signals of the mushroom type in their installation have been 25 provided with one or more electric lamps or bulbs for illuminating purposes, and owing to this fact an expensive installation is necessary, due to excavation and the provision of means for renewing such lamps.

30 My invention therefore contemplates eliminating all of this expensive installation work whereby the cost of the apparatus and its maintenance thereafter is reduced approximately seventy-five percent, or more.

35 Aside from the economic value mentioned above, the advance in the art of mushroom traffic signals made by me eliminates the serious objections to such devices, which is that under traffic conditions the mushrooms 40 are frequently struck by passing vehicles and the vibration will break or damage the lighting units to such an extent as to render the signal dark and inoperative.

It is also understood that my invention 45 may be applied to any type of mushroom.

With the above objects in view, the invention consists in the method and mechanism, as hereinafter set forth with reference to the accompanying drawings and subsequently 50 claimed.

In the drawings:

Figure 1 represents a diagrammatic sectional elevation of a mushroom traffic signal embodying the features of my invention, and

55 Figure 2 is a plan view of the same.

Referring by characters to the drawing, 1

represents a skeleton dome having openings fitted with transparent signal plates 2 therein, which signal plates may be of colored glass, or they may have certain indices 60 placed thereon. As shown the dome is provided with four signal plates equidistantly apart to deflect rays of light in alinement with the intersecting streets, but it understood that these signal plates may be varied 65 in number, or the dome may be made up to deflect the light rays from a practically continuous surface at angles that will come within the line of vision of parties entering the field of the point of intersection of 70 the streets.

The dome, as shown, is open at its crown whereby the rays of light from a fixed illuminating source overhead, will enter and said dome has nested therein a centrally disposed deflector 3, which deflector is suitably centered and supported by a base plate 4 which is secured to the rim of the dome, as shown. Obviously the deflector 3 may be 80 varied in form. As for example, it may be concave or convex in the shape of a basin, or otherwise. Said reflector may also, without departing from the spirit of my invention, be formed of a plurality of separate units corresponding in number to the signal 85 plates.

The circle, or crowned dome, as shown, is anchored by the ends of the retaining bolts 5, but obviously any means can be provided for this purpose, and it is apparent that the dome can readily be dropped into position under the lamp 6, or source of fixed light, without any previous excavation or work upon the surface of the street. Obviously this advantage is material to the fact that 90 installation of the device can be quickly performed without any extra work and by those unskilled in the art of anchoring or affixing such devices.

From the foregoing description it will be 100 readily understood that the ordinary arc-light, which is usually positioned at the intersecting streets, is utilized to illuminate the crossing signal indicator, and that the rays of light, by a deflector within the mushroom, are directed through the signal plates in four directions for safety purposes, whereby the dome is practically and clearly illuminated without extra cost in lamp power or apparatus. In some instances the 105 arclights or lamps are positioned at the street corners, in which case each lamp will 110

deflect its rays towards the mushroom dome and function to illuminate it, it being understood that the illuminating unit is suspended overhead at all times and that it is fixed and so arranged relative to the dome that the light rays will be unobstructed.

I claim:-

1. A mushroom traffic indicator arranged to receive and reflect rays of light from a remote fixed illuminating source, the same comprising a skeleton dome having transparent signal plates therein and a centrally disposed reflector adapted to deflect the rays of light through said signal plates.

2. A mushroom traffic indicator arranged to receive and reflect rays of light from a remote fixed illuminating source, the same comprising an opaque skeleton dome having transparent signal openings therein and a centrally disposed reflector adapted to deflect the rays of light through said signal openings.

In testimony that I claim the foregoing I have hereunto set my hand at Milwaukee, in the county of Milwaukee and State of Wisconsin.

CHARLES L. PAINE.
